LOOSE-LEAF BINDER

Hubert Auburn, Mount Healthy, Ohio, assignor to
The Tenacity Manufacturing Co., Lockland,
Ohio, a corporation of Ohio

Application May 23, 1941, Serial No. 394,913

4 Claims. (Cl. 129—24)

This invention relates to improvements in loose leaf binders of the so-called record book type.

An object of the present invention is to provide in a loose leaf binder of the record book type a mechanism for automatically moving the pintle slides to a closed position when the impaling posts are seated within their respective pintle-slide-bar-housing notches.

The present invention is directed, among other things, to the provision of simple, inexpensive, yet highly efficient means for automatically actuating the pintle engaging means of a loose leaf binder in such a manner as to obviate objectionable features found in the present day binder structures.

A further object of the invention is to provide an automatic pintle closing device which includes an impaling post actuated trip member which is adapted to release the pintles from a non-impaling post engaging position to an impaling post engaging position.

These and other objects are attained by the means described herein and disclosed in the drawing in which:

Fig. 1 is a fragmentary end elevational view of a loose leaf record binder embodying the present invention, with one cover in an open position.

Fig. 2 is a top elevational view of the binder of Fig. 1.

Fig. 3 is a fragmentary plan view of a pair of pintle slide bars and a latch member which comprise a binder locking mechanism, and an impaling post, showing the relationship of the indicated elements just as the impaling post is being moved against the latch member for releasing the pintle slide bars to an impaling post engaging position.

Fig. 4 is a fragmentary longitudinal, sectional view through the tubular pintle-slide-bar-housing 18 of the binder, showing the locking mechanism of Fig. 3 housed therein.

Fig. 5 is an enlarged view of the latch member of Fig. 4 with slide bar 21 removed for clarity of detail and understanding.

Fig. 6 is a side plan view of an impaling post.

Fig. 7 is a top plan view of the impaling post of Fig. 6.

As disclosed in the drawing binder structures embodying the teachings of the present invention may comprise a back member 10 having its longitudinal edges rolled to provide a plurality of aligned, spaced hinge barrels 11, and a pair

of cover sections 12 and 13, secured to and carried by wing members 14 and 15 one edge of each of which is provided with aligned spaced hinge barrels 16 which are complementary to hinge barrels 11 of back member 10, as disclosed in Fig. 2. Wing members 14 and 15 may be hingedly secured to the opposite longitudinal edges of back member 10 by means of rods 17.

A pair of tubular pintle slide bar housings 18 may be permanently and rigidly secured to the opposite longitudinal edges of back member 10, by any suitable means, such as by welding, bolting, or the like. The upper or outer edges of housings 18 are preferably provided with a plurality of spaced notches 19 each of which are adapted to receive one end of an impaling post 20. Reciprocable means may be mounted in said housings for releasably securing the impaling posts relative to back member 10. Such means 20 may comprise a pair of complementary pintle slide bars 21 and 22 which may be suitably mounted for simultaneous movement in opposite directions along a common longitudinal axis by means of the double rack and pinion mechanism denoted generally by the numeral 23 of Fig. 3. Each pintle slide bar is provided with a plurality of pintles 25 which are adapted to engage apertures 26 provided in the opposite ends of impaling posts 20 for releasably engaging said posts for maintaining sheets thereon, and for securing said posts relative to back member 10.

Resilient means, such as spring 27 of Figs. 3 and 4, may be provided for normally and yieldingly urging the pintle slide bars to a pintle-post engaging position. It should be understood that in the structures disclosed in Figs. 3 and 4, spring 27 normally urges pintle slide bar 21 in the direction indicated by arrow 28, and pintle slide bar 22 is normally urged in the direction indicated by arrow 29, whereby pintles 25 of the respective pintle slide bars are normally urged toward one another for engaging opposite ends of apertures 26 of impaling posts 20. It should be noted that although but one set or pair of pintles are illustrated in Fig. 3, actually there is a set or pair of pintles for each of the impaling posts to be engaged, viz. five of Fig. 2.

Releasable means such as spring actuated trip 50 or latch member 30 may be provided for releasably maintaining the reciprocable pintle slide bars 21 and 22 in the inoperative or non-post-engaging position disclosed in Figs. 3 and 4. Latch member 30 may comprise a piece of material such as sheet metal, or the like shaped

to include an impaling-post-contact-portion 31 and a pintle slide bar engaging hook 32. Latch 30 may be mounted for pivotal movement about pivot pin 33 which may be carried by wing 34 of an L-shaped bracket 9, wing 35 of which may be suitably secured relative to back member 10. Suitable means, such as spring 36 may be provided for yieldingly urging pintle slide bar hook 32 against edge 37 of pintle slide bar 22 whereby to automatically engage offset 38, provided in edge 37, whenever slide 22 has been retracted to the position disclosed in Fig. 3. It will be observed that pintles 25 will be maintained in the inoperative position of Figs. 3 and 4 so long as hook 32 of latch member 30 engages offset 38. Latch member 30 is preferably located adjacent notch 19 with its impaling-post-contact portion 31 disposed intermediate the adjacent side edges of said notch, as disclosed in Fig. 4.

Latch member 30 may be simply yet positively released from its pintle slide bar engaging position incident to the introduction of an impaling post 20 thereagainst in the direction indicated by headed arrow 39. As post 20 is moved to the left, latch member 30 will be pivoted about pin 33 thereby effecting disengagement of hook 32 from offset 38. The moment such disengagement is complete pintles 25 will be shifted to a post engaging position under the influence of spring 27. It should be understood that it is necessary to provide but one trip or latch member for the pintle slide bars housed within each tubular housing 18, since all of the various impaling posts of any particular binder will, under all normal conditions, simultaneously engage notches 19 of a pintle-slide-bar-housing, whereby all of the impaling posts may be simultaneously engaged by their respective pintles carried by the pintle slide bars.

Impaling posts 20 are adapted to be disconnected from back member 10 when the pintle post bar 21 has been manually withdrawn from tubular housing 18 against the counterforce of the spring means which normally urge the pintle slide bars to a pintle impaling post engaging position. As soon as pintles 25 have been shifted by an amount to be completely withdrawn from apertures 26 of the various impaling posts 20 comprising a binder, the trip or latch member 30 is adapted to releasably engage pintle slide bar 21 for maintaining the pintles in a non post-engaging position.

The pintle slide bar may be released from an inoperative position when the trip or latch member is depressed incident to the insertion of an impaling post into its associated notch 19. Each impaling post is adapted to be freely inserted into its respective tubular-housing-notch 19 whereby to locate aperture 26 in alignment with the longitudinal axis of the pintles. It will be observed that the impaling post is not subjected to wear or mutilation incident to actuation of the trip or latch members.

From the foregoing it is apparent that the locking mechanism of the present invention is rendered operative by an impaling post whereby the locking operation occurs while the covers are open and under the very eyes of an operator.

It should be observed that the impaling posts may be introduced into their respective tubular-housing-notches 19 by urging cover member 12, Fig. 1, to the right in the direction indicated by headed arrow 60, for shifting the uppermost tubular housing 18 toward the upper apertured ends of impaling posts 20, whereby the

record sheets 61 impaled on posts 20 and cover 13 will assume the relative positions disclosed. An alternative method of introducing impaling posts 20 into notches 19 is to hold cover 12 in the position indicated in Fig. 1 and apply force to sheets 61 in the direction indicated by the headed arrow 62 for pivoting the impaling posts about their respective pintle connections with the lowermost tubular housing 18.

It will be observed that the actuation of latch member 30 is entirely independent of the relative location or position of cover members 12 and 13, whereby the impaling posts of a record binder may be automatically engaged while the binder is in an open condition. It should likewise be observed that inasmuch as each of the various impaling posts are engaged by their respective pintles only after said posts have been fully seated within their respective notches 19 of tubular housing 18, said posts are not and cannot be subjected to mutilation and wear. Impaling post wear and mutilation presents a serious and sizable problem to the users of record type loose leaf binders, which problem has been not only solved, but is completely obviated by the present device. Heretofore efforts have been made to solve the problem of wear and mutilation to which the impaling posts are subjected by constructing them with special impaling posts which, though more expensive than the so-called standard impaling posts as disclosed in Figs. 6 and 7, have nevertheless failed to satisfactorily solve the problem. Inasmuch as the locking mechanism of the present invention does not depend upon any special characteristics of the impaling post which actuates the latch member, the present device may be operated with maximum efficiency using the so-called standard, inexpensive impaling posts of Figs. 6 and 7, which are easily obtainable throughout the civilized world.

What is claimed is:

1. In a device of the class described, the combination of a binder comprising a back member, a tubular housing secured to said back member and having notches in the edge thereof, posts for cooperation with the edge notches of said housing, a pair of oppositely movable pintle bars located within said housing and including pintles for each post, means for yieldingly urging said bars to post engaging positions, a latch member located at one of said notches, cooperating means associated with said latch member and one of said pintle bars for releasably maintaining said pintle bars in inoperative position out of engagement with said posts and against the counterforce of said first mentioned means, said latch member adapted to be engaged by a post for releasing said pintle bars to automatically engage said posts incident to movement of the posts into the notches of said housing.

2. In a device of the class described the combination which comprises a back member, a tubular housing rigidly secured to and carried by said back member and having notches in the edge thereof, sheet impaling posts having ends adapted to be received in said notches, a pair of oppositely movable pintle bars located within said housing and including pintles for each post, means for yieldingly urging said bars in opposite directions to post engaging positions, a rack and pinion connection between said bars for synchronizing their relative movements, means for holding said pintle bars out of post engaging position, said means being released when engaged by an

impaling post incident to the seating of said post within its respective housing notch for releasing said post engaging bars to post engaging position.

3. In a device of the class described a binder comprising in combination, a back member, a pair of inverted U-shaped pintle rod housings rigidly secured to the opposite longitudinal edges of said back member and having notches provided in the upper edges thereof, impaling posts having ends adapted to be received within said notches, a pair of oppositely movable pintle slide bars located within said housing and including pintles for each post, means for yieldingly urging said pintle slide bar members in opposite directions to post engaging positions, a rack and pinion connection between said pintle slide bars for synchronizing their movements, of a latch member including an impaling post contact portion and a pintle slide bar engaging hook, a latch support located externally of and adjacent one of said notches, said latch mounted to said latch support by a pivot pin whereby said impaling post contact portion and the pintle slide bar engaging hook of said latch are disposed on opposite sides of said pivot pin, hook engaging means provided in that pintle slide bar adjacent said latch support, said impaling post contact portion dimensioned for movement about said pivot pin in said notch and in the plane of that wall of the pintle slide housing adjacent said latch support, said hook adapted to engage said hook engaging means of said pintle slide bar for releasably locking said pintle slide bars in an inoperative retracted position, said latch adapted to be disengaged from said pintle slide bar incident to the insertion of an impaling post into said notch and the alignment of the ends of said pintle posts with their respective pintles whereby the impaling posts will be simultaneously engaged by their respective pintles incident to movement of the pintle slide bars to a closed, impaling post engaging position.

4. In a device of the class described a binder comprising in combination, a back member, a pair of inverted U-shaped pintle rod housings

rigidly secured to the opposite longitudinal edges of said back member and having notches provided in the upper edges thereof, impaling posts having ends adapted to be received within said notches, a pair of oppositely movable pintle slide bars located within said housing and including pintles for each post, means for yieldingly urging said pintle slide bar members in opposite directions to post engaging positions, a rack and pinion connection between said pintle slide bars for synchronizing their movements, of a latch member including an impaling post contact portion and a pintle slide bar engaging hook, a latch support located externally of and adjacent one of said notches, said latch mounted to said latch support by a pivot pin whereby said impaling post contact portion and the pintle slide bar engaging hook of said latch are disposed on opposite sides of said pivot pin, hook engaging means provided in that pintle slide bar adjacent said latch support, said impaling post contact portion dimensioned for movement about said pivot pin in said notch and in the plane of that wall of the pintle slide housing adjacent said latch support, said hook adapted to engage said hook engaging means of said pintle slide bar for releasably locking said pintle slide bars in an inoperative retracted position, said latch adapted to be disengaged from said pintle slide bar incident to the insertion of an impaling post into said notch and the alignment of the ends of said pintle posts with their respective pintles whereby the impaling posts will be simultaneously engaged by their respective pintles incident to movement of the pintle slide bars to a closed, impaling post engaging position, the impaling post contact portion of said latch being so disposed relative to said notch and impaling post engaging pintles therefor so as to preclude accidental or unintentional tripping of said latch until said impaling posts are disposed in their respective notches and aligned relative to their respective pintles.
